(57) **CLAIM**

The ornamental design for a collection bag, as shown and described.

DESCRIPTION

FIG. 1 is a perspective view of a collection bag, showing the new design.

FIG. 2 is a front elevational view of the collection bag of FIG. 1.

FIG. 3 is a rear elevational view of the collection bag of FIG. 1.

FIG. 4 is a bottom plan view of the collection bag of FIG. 1.

FIG. 5 is a top plan view of the collection bag of FIG. 1.

FIG. 6 is a right side elevational view of the collection bag of FIG. 1, the left side thereof being a mirror image.

FIG. 7 is a perspective view of a second embodiment of the collection bag, showing the new design.

FIG. 8 is a front elevational view of the second embodiment.

FIG. 9 is a rear elevational view of the second embodiment.

FIG. 10 is a bottom plan view of the second embodiment.

FIG. 11 is a top plan view of the second embodiment; and, FIG. 12 is a right side elevational view of the second embodiment, the left side thereof being a mirror image.
